UNITED STATES PATENT OFFICE.

RICHARD TODD, OF HEATON CHAPEL, AND JESSE AINSWORTH STOTT, OF MANCHESTER, ENGLAND.

APPARATUS FOR SPINNING TEXTILE FIBERS.

SPECIFICATION forming part of Letters Patent No. 603,068, dated April 26, 1898.

Application filed November 10, 1896. Serial No. 611,649. (No model.) Patented in England November 7, 1895, No. 21,056.

To all whom it may concern:

Be it known that we, RICHARD TODD, manufacturer, of Heather Bank, Heaton Chapel, and JESSE AINSWORTH STOTT, architect and engineer, of 5 Cross street, Manchester, in the county of Lancaster, England, subjects of the Queen of Great Britain and Ireland, have invented certain new and useful Improvements in Apparatus for Spinning Textile Fibers, (for which we have obtained a patent in Great Britain, No. 21,056, dated November 7, 1895,) of which the following is a specification.

Our invention relates to improved means for spinning yarns upon the bare spindle of the ordinary diameter in frames principally of the throstle type. Under our invention the spinning is effected by the aid of an elastic whip-traveler and by mechanism the principle of which is set forth in certain prior United States patents, Nos. 40,957, 40,958, 40,959, and 40,960, granted to Ernst Gessner and now in force and also in a patent in Great Britain, No. 20,487 of 1894, granted to one of the present applicants, Richard Todd. In the specifications of the said patents a ferrule or ring fits the spindle loosely and carries a fixed rigid or elastic arm or whip-traveler having an eye at the upper end through which the yarn passes to the cop or spindle. In the said foregoing specifications, and especially in the said British specification of Todd, the said arm or whip-traveler is a fixture on the ferrule or ring, and this is the source of many disadvantages both in the course of manufacture and use. For example, the arm is apt to break at the bend, and if such should happen or should the arm or whip-traveler become otherwise unfit for use the whole ferrule or ring requires to be removed from the ring or race in which it is retained by bent fingers and either repaired or thrown away, both time and material being thus sacrificed. Under our present invention we remedy these defects by making the arm or whip-traveler separate from the ferrule or ring and forming both so that the arm can be readily attached or detached at pleasure and without removing the ferrule from the race. The most convenient method is to form any suitable spring snap-joint, the socket to receive the butt of

the whip-traveler being formed either directly on the ferrule or ring or on an arm or projection therefrom. When the socket is formed in a projection from the ferrule, the 55 arm or whip-traveler may be made perfectly straight from butt to tip or eye, which is a great convenience for cheap manufacture. We might bend or form the foot of the arm so as to form a spring-butt snapping into a 60 recess in the socket or we might form the socket with a spring-catch to engage with the butt of the arm. When a spring snap-joint is used, a tongue prolongation or presser may be provided to effect a more ready disengagement and separation of the arm from the ferrule. A spring snap-joint, however, is not 65 essential, as any other convenient means, such as a jam-ring or other ready means, might be used to effect the purpose of our invention, which is to render the arm or whip-traveler separate from and readily attachable to and detachable from the ring or ferrule. 70

By means of our invention we effect great economy both in time and material and remove a source of mischief and loss which militated greatly against the commercial success of this type of spinning appliance. 75

Our invention also relates to improved means for more readily and easily mounting 80 the aforesaid ring or ferrule, which carries the whip-traveler, in working position. Under the construction set forth in the said prior British specification of Richard Todd the said ring or ferrule is provided at the foot with 85 bent fingers, two being the most suitable number, which fingers run in a race formed in a socket-ring with cap, the said socket-ring being carried in a lifting rail or part beneath the cop. As it is extremely desirable, if not 90 indeed essential, to have the confining race as small in diameter as possible, so as to diminish the frictional resistance or drag upon the said fingers, it was under the said prior arrangement necessary to introduce the fingers first into the socket-ring and bend them out afterward or otherwise during the process of introduction. This was an operation which took considerable time and care and interfered materially with the economical use 95 100 of the invention. Under our present invention the fingers can be properly bent and

shaped before being placed in the race of the socket or carrying ring. To effect this, we so form the ferrule that it becomes possible and easy to slip the bent fingers of the ferrule into working position in the race. Under the method which is most likely to be adopted we cut out or shape the sides of the ferrule opposite to the fingers so that the sides of the ferrule offer no obstruction to the insertion of the bent fingers. One result of so cutting out the ferrule is that it becomes thereby greatly lightened. To facilitate the application of the cap or cover of the socket or carrying ring, we make it of such a size that it can be passed down through the curbing-sleeve, which surrounds and confines the whip-traveler. As this materially restricts the diameter of the said cap, we use a secondary cover-plate to cover in the socket or carrying ring, and this cover-plate may be made in two or more parts. The cover-plate is cut out in the center to receive the cap. Thus the cap may be made small enough to pass through the curbing-sleeve without reducing the size of the carrying or socket ring.

In order that our said invention may be fully understood, we will now proceed to describe the same more particularly, reference being had to the annexed three sheets of illustrative drawings.

On Sheet 1, Figure 1 is a general view of a spindle carrying a wound-on cop of yarn and furnished with a flexible whip-traveler of the indicated description. On Sheet 2, Figs. 2 to 35 illustrate various modes of rendering the elastic or whip traveler readily attachable to and detachable from the arm of the ferrule or part mounted loosely on the spindle. On Sheet 3, Figs. 17 to 20 show an improved mode 40 of cutting out or shaping the ferrule or loose part mounted on the spindle, so that it can be inserted into position in the ring-socket after the fingers at the foot of the ferrule have been bent to the proper shape. Figs. 21 and 45 22 show a mode of making the arms of the ferrule readily attachable and detachable. Figs. 23 and 24 show our improved modes of introducing the cap or cover of the socket-ring through the curbing-sleeve and of retaining the socket and cap in position.

Referring to Sheet 1 of the drawings, Fig. 1 has been inserted chiefly for the purpose of making the general arrangement and construction of the spindle and flexible whip-traveler more clear to the reader. The spindle A is supported in the bolster-rail in the ordinary manner and is driven from the whirl A'. In this figure a cop B is shown wound on the spindle. The flexible arm or whip-traveler C is carried on an arm D' of the ferrule D, which is loosely mounted on the spindle. A balancing-arm D² exists on the other side of the ferrule. The ferrule D has projecting fingers D³, which run in a space between the two halves of a socket-ring E E', the said socket-ring being held in a lifting-rail F, which rises and falls, so as to correspondingly

raise and lower the eye C' of the whip-traveler C. The space behind the ledges constituting the rail to receive the fingers D³ forms an oil-chamber to contain lubricant. Above the rail F and carried in another rail F' is a curbing-ring G, which surrounds the cop and prevents the whip-traveler C from flying outward by centrifugal force. When the apparatus is at work and the building of the cop B is in progress, the whip-traveler C is rotated by the draw of the yarn in the same direction as the revolution of the spindle, and the yarn is spun and drawn through the eye C' just as in the case of a ring-traveler; but suppose the yarn to be winding on the bare spindle or cop-sleeve or on any part of the cop where from the directness of the pull or from other causes a strain greater than usual is thrown upon the yarn, then instead of pulling upon an unyielding object like the ordinary traveler (which only runs with greater friction and hangs farther back the more directly radially the yarn pulls upon it) under our improvement the yarn pulling on the elastic arm C draws the eye C' close up to the spindle or cop and canting the ferrule D on the spindle binds it thereon or causes it to have more frictional contact therewith, so as to accelerate its speed, so that the whip-traveler offers less resistance and breakage of the yarn is prevented. This general sketch of the operation of the flexible whip-traveler and parts will assist the reader to follow more intelligently the improvements which constitute our present invention.

The general principle as disclosed in Gessner's and Todd's specifications has never been followed up or made practically and commercially successful because of the insufficiency and impractical nature of the details. For example, it has hitherto never been proposed to do otherwise than make the flexible arm C in one piece with the ferrule D. Such a method of construction is subject to the disadvantage that the ferrule and arm are difficult to make in one piece and are easily broken. The result of such a breakage is that not only the arm but the ferrule also is rendered useless and the ferrule requires to be removed and renewed.

According to our invention we make the flexible arm C easily attachable and detachable from the ferrule, so that if the flexible arm should be disabled or broken it can easily be replaced without disturbing the ferrule. This detachability of the flexible arm or whip-traveler C from the ferrule is the essence of this portion of our invention. It will be evident that various means for quickly attaching and detaching the arm or whip-traveler might be used. We do not confine ourselves to any particular method; but in order to give illustrations of several ways in which it can be done we have appended in Sheet 2 illustrations of several methods which we have tested and found efficient.

In the drawings each figure, as a rule, covers and includes a sectional view and a plan.

For example, as in Fig. 2, we form the arm D' of the ferrule D with an oblong socket D⁴ or aperture, and we form the tail of the flexible arm C with a spring-elbow, which snaps 5 into the oblong socket, the curved end of the elbow entering a hole in the side of the socket. By pinching together the projecting portion 10 of the elbow at the foot the arm C can be disengaged and drawn out. Fig. 3 shows a similar arrangement, the free end of the spring-elbow on the arm C having a stamped-out projection C², which enters a similarly-shaped aperture or recess in the side of the socket D⁴. The free end of the elbow projects above 15 the socket D⁴, and by pinching this toward the arm C the latter can be disengaged. Fig. 4 is identical with Fig. 3, except that the pressed-out locking or snap projection C' is on the same side of the elbow as the flexible arm C. 20 In Fig. 5 there is no spring-elbow. The arm C has a projection C'', which enters a recess in the socket D⁴, the arm being kept in position by a tapered cotter H, driven down so as to wedge the tail of the arm C in position. In 25 Fig. 6 there is a spring-tongue D⁵, stamped out of the material of the socket D⁴, and having a ridge at the back which engages with a bend or crook C²¹ on the tail of the arm C. By pushing down the tail of the arm C into the socket D⁴ it 30 snaps behind the spring D⁵, and by lifting the spring D⁵ the tail can be released again. In Fig. 7 the socket has beneath it a pressed-out tooth or stop D⁶, which enters the loop of the elbow at the foot of the arm C. The free end 35 of the elbow has an inclined termination C⁸, which acts as a wedging-spring to draw up and hold the elbow against the tooth or stop D⁶. In Fig. 8 the socket D⁴² itself is formed as a spring-eye to nip and hold the flexible 40 arm C. The foot of the arm C is formed with an eye engaging with a tooth or stop D¹⁶. In Fig. 9 the same formation of spring-socket is used, the foot of the arm C having a portion 45 bent at right angles, which snaps into a hole in the arm beneath the socket. In Fig. 10 the foot of the arm C has a pressed projection or knee C²¹, which snaps into a recess made to receive it in the spring-socket D¹⁴. In Fig. 50 11 the crooked foot C²¹ of the arm C is held in position by a cover D⁷, which is slid over the arm D' after the part C has been placed in position. The arm D' might either be flat across, as shown in the lower plan view, or it might be recessed to receive the foot of the 55 flexible arm C, as shown at D'' in the plan Fig. 11^a. In Fig. 12 the flexible arm C is held to the end D¹⁰ of the ferrule-arm D' by a sliding jam-ring D¹⁷. In Fig. 13 the cover D¹⁸ is hinged to the arm D', so as to turn over the 60 traveler-arm C and secure it. In Fig. 14 the foot of the flexible arm C is made with a spring loop or eye, which engages with the suitably-shaped part D¹³ of the arm D'. In Fig. 15 the spiral or corkscrew formed foot of the flexible arm C is dropped into the socket D²⁴ and held by a projecting finger engaging in a notch, while in Fig. 16 the similarly spi-

ral shaped foot of the arm C fits upon the cylindrical projection D¹⁵ from the arm D' and is held by a finger projecting inward and engaging in a notch. In all of these different forms the flexible arm C is readily attachable to and detachable from the arm D', so that if the flexible arm C should at any time be disabled or broken it can easily and speedily be removed and replaced by a fresh arm without disturbing the ferrule. Although we have shown so many forms of this improved detachable connection between the ferrule-arm and the whip-traveler, we do not, of course, confine 70 ourselves to these, and consider any ready means of attaching and detaching the whip-traveler as within the scope of our invention. Our invention also relates to improved means for enabling the ferrule D to be more 85 easily applied when the fingers D³ have been bent to the proper angle and shape. When using a socket-ring, such as E E', (shown in Fig. 1,) it is essential to limit the confining race as much in diameter as possible, so as to 90 diminish the frictional resistance or drag upon the said fingers. In former cases—for example, in the aforesaid former specification of Richard Todd, No. 20,487 of 1894—it was necessary to introduce the fingers first into 95 the race and then to bend them outward at right angles to the ferrule. This was an operation which took considerable time and care and interfered materially with the economical use of the invention. Under our present 100 invention the fingers can be properly bent and shaped before being placed in the race of the socket-ring. To effect this, we so cut out or form the ferrule that it becomes possible and easy to slip the bent fingers of the 105 ferrule into working position in the race. This new mode of forming the ferrule is shown in Figs. 17 to 20, Sheet 3. We cut out or shape the sides of the ferrule D opposite to the fingers D³. When this is done, the fingers can 110 be inserted into the race, the cut-out sides of the ferrule allowing it to be canted in the manner shown at Fig. 19, thereby permitting of the introduction of the fingers D³ into the race. The spindle A may then be passed up- 115ward or downward through the ferrule and socket-ring. Not only does this cutting out of the ferrule enable the bent fingers D³ to be introduced into the socket-ring race, but it has also the advantage of greatly lightening 120 the ferrule and reducing frictional drag. Another method of introducing the already-bent fingers D³ of the ferrule into the race is to render the arms D' D² detachable from the ferrule D. This improvement is illustrated 125 in Figs. 21 and 22. Fig. 21 is a vertical section of the ferrule and separately-applied arms, and Fig. 22 is an exterior view of the ferrule without the arms, but with the upper half or cap of the socket-ring shown surrounding the ferrule. The ferrule D is formed with its fingers D³ bent to the proper shape and set. The ferrule is also formed with side snap-springs d, pressed out of the ma-

terial. The arms D' D^2 are formed in one piece with a ring D^8 , from which the arms spring. The ring D^8 is formed with perforations to receive projections d' from the springs d . In applying the ferrule we place the fingers D^3 on the race of the lower half of the socket-ring, then place the upper half of the socket-ring in position, slipping it over the ferrule, and then snap the ring D^8 , carrying the arms, upon the upper spring portion of the ferrule.

Figs. 23 and 24 illustrate improved means for introducing and holding down the caps E' of the socket-rings E . We effect this by means of clips J , secured to the lifting-rail F by screws K . This enables us to dispense with threading the cap and socket to screw them together, as in the said prior specification of Todd, or the provision of screwed studs to connect the ring and cap.

It is advisable to provide that the cap E' shall be capable of being passed down into position through the curbing-sleeve G . Therefore we seek to reduce its diameter as much as possible. In Fig. 23 a ledge E^4 is formed in the interior of the socket-ring E , this ledge receiving and supporting the outer edge of the cap E' . The clips J , extending over the cap and ring, hold the cap in position. As the dotted lines show, the cap is sufficiently small to pass through the curbing-sleeve G . In Fig. 24 a separate annular cover plate or ring L is seated in a check or recess in the socket-ring E , and the cap E' is placed over this annular ring L , the clips J holding both ring and cap in position. In this instance also, as the dotted lines show, the cap can be passed through the curbing-ring G .

We claim as our invention—

- 40 1. In combination the spindle to carry the cap, the ferrule arranged about the spindle at a point below the position of the cap, and the whip-traveler attachably and detachably secured to the ferrule below the cap and extending up along the cap with its free end directed upwardly, the attachment between the traveler and the ferrule being rigid while the said whip is flexible and adapted to bend throughout its length.
- 45 2. In combination, the ferrule on the whip-traveler arm, said ferrule having an extended bearing or socket adapted to receive the lower end or butt of the arm and afford an

extended bearing thereto, said arm-butt being formed as a spring to engage with and be easily disengaged from the extended bearing, substantially as described.

3. In combination with the rotary foot or ferrule with means for supporting the same, the arm extending laterally from said ferrule having a terminal-bearing part at its end, and the flexible arm or traveler arranged to turn about the spindle with said rotary ferrule, said arm being detachably connected with the terminal-bearing part of the said ferrule, substantially as described.

4. In combination, the ferrule having a socket, and the flexible arm or whip-traveler having a spring portion to fit therein, substantially as described.

5. In combination the ferrule having a socket with a lateral cavity, and a flexible arm or traveler having a laterally-extending portion fitting into said cavity, substantially as described.

6. In combination, the ferrule having a socket with a lateral cavity, a flexible arm or whip-traveler having a spring end provided with a laterally-extending portion to fit the cavity, substantially as described.

7. In combination, the ferrule having a laterally-extending arm with a terminal bearing, and a flexible arm or whip-traveler having a spring end detachably engaging the same, substantially as described.

8. In combination with the socket-ring and its cover forming a race between them and the ferrule having the fingers adapted to the race and its sides recessed to permit the insertion or removal of the ferrule, substantially as described.

9. In combination, the socket, the cover, the whip-traveler and the ferrule, one of said parts, the cover or the ferrule being laterally recessed to permit the insertion or removal of the ferrule by tilting the same.

10. In combination, the socket-ring, the cover, and the clips J for holding the same in place, substantially as described.

In witness whereof we have hereunto set our hands in presence of two witnesses.
